Inventor:

John Alexander Leggatt.
By John H. Hendry Atty.

UNITED STATES PATENT OFFICE.

JOHN ALEXANDER LEGGATT, OF HAMILTON, CANADA.

ELECTRIC-LIGHT ADJUSTER.

SPECIFICATION forming part of Letters Patent No. 690,113, dated December 31, 1901.

Application filed June 1, 1901. Serial No. 62,709. (No model.)

To all whom it may concern:

Be it known that I, JOHN ALEXANDER LEGGATT, a citizen of Canada, residing at Hamilton, in the county of Wentworth and Province 5 of Ontario, Canada, have invented certain new and useful Improvements in Electric-Light Adjusters; and I do hereby declare the following to be a full, clear, and exact description of the invention, such as will enable 10 others skilled in the art to which it appertains to make and use the same.

My invention relates to improvements in electric-light adjusters in which a certain flanged cup or socket is secured to a ceiling 15 or wall, a ball with lower shank in the lower part of the socket, the shank protruding through the socket, a vertical tube secured to the shank, and a tube with electric light capable of telescoping in said secured and 20 outer tube.

The objects of my invention are, first, to provide an electric light which is capable of being adjusted from the vertical to various angles or oblique positions radiating from the 25 center of the supporting-ball; second, to provide means for staying the electric light in desired vertical or other position; third, to afford facilities for raising or lowering the light, and, fourth, to provide means for staying the 30 light to any desired raised or lowered position. I attain these objects by the mechanism illustrated in the accompanying drawings, in which—

Figure 1 is a sectional elevation of the electric-light adjuster, also two of the many positions, in broken lines, to which the light 35 may be adjusted. Fig. 2 is an elevation of the detached cross-bar of the cup. Fig. 3 is a plan of the same. Fig. 4 is an elevation in 40 detail of the ball with shank and cap. Fig. 5 is a detail plan of the ball. Fig. 6 is an enlarged detail elevation of the upper end of the slidable tube with spring-arms for holding the tube in position, and Fig. 7 is a plan of 45 Fig. 6.

Similar characters refer to similar parts throughout the several views.

In the drawings the upper cup or socket is indicated by A and is provided with an annular flange or lugs 2 for securing the same 50 to a ceiling B or to a wall, as the case may be. The socket A may be of various shapes and

designs; but the lower or socket part proper must of necessity be round and of socket formation to suit the ball C. The lower part of 55 this socket has an opening 3 to allow the shank D of the ball C to pass through. This opening 3 is about twice as large in diameter as the diameter of said shank D in order to allow the shank, with its appendages, to be placed or 60 adjusted to different oblique positions. The ball, together with its shank D, has a through vertical opening 4 to allow the electric wire E to pass through. A vertical tube F is secured to the shank D and is suspended therefrom, and the lower end of the tube F is provided with a reducing-collar H, which is 65 screwed onto the end of said tube F. This collar H has a central vertical opening 5 of the same diameter as the diameter of the inner slidable tube J. The slidable tube J is 70 capable of sliding through the opening 5 of the collar H when manipulated. The lower end of the slidable tube J is provided with an electric-light device K, which is secured to 75 the tube in approved manner. The upper end of the tube J is provided with a secured inner ring M, with outer projecting and suitably curved spring-arms N, which when 80 pressed toward the center of the tube J said tube is capable of entering the outer tube F, and the arms N then press outward and press against the inner sides of the tube F and retain the tube J in manipulated position. The said arms N will allow the tube J to slide 85 in the tube F by the inherent resiliency of the spring-arms.

The ball C has a cap P. Said cap has a through central opening 6 for the passage of the electric wire E. The lower concaved 90 face of this cap P rests upon the ball C, and the upper flat face of the cap P is connected to the upper bar R by means of the spiral pressure-spring S, which presses against the bar R and the cap P to stay the ball C. The 95 bar R fits against the lower part of the inner flange 7 of the cap or socket A. The bar R may be inserted into position and also the ball C and cap P through the upper opening of the socket A previous to securing the 100 socket to the ceiling B. The bar R has a central opening 10, which is continued through its central boss 8 for the passage of the electric wire E. The cap P has a central boss 9 to con-

form to the central boss 8 of the bar R. These two bosses 8 and 9, respectively, fit into the ends of the pressure-spring S to retain the spring in proper and relative position to the bar R 5 and the cap P. The tension of the spring S is to press upon the cap P in order that the cap may press upon the ball C and retain the ball in desired position in the socket A when the tubes F and J are brought to other positions 10 as well as to vertical position, as shown. The electric wire E is connected at one end to its source of power, and the other end of the wire is passed through the central openings of the bar R, the spring S, the cap P, the 15 ball C, and its shank D. The wire E is then allowed to coil, as shown, in ample length in the tube F to allow the tube J, with the electric light K, to be brought downward to its limit. The electric wire then passes through 20 the central opening of the ring M, thence through the vertical tube J, and into the ordinary electric device or light K, which is secured to the end of the tube J.

It will be obvious that when the ball is manipulated by means of its connected tubes 25 the electric wire E would bind if it were not for the spread or flaring out of the upper part of the vertical and central opening 4 through the ball C. The opening 6 through the cap 30 P is also flared out at the lower concaved part in like manner as the upper flare of the central opening of the ball to prevent or counteract any possible binding of the electric wire E when the electric light is being manipulated 35 to a different position.

The described method of holding an electric light in a desired place and position is very desirable, especially so in various operations and professions where it is necessary to 40 have the light in close proximity to the object of sight.

Various changes in the form, proportion, and minor details of this invention may be re-

sorted to without departing from the spirit and scope thereof. Hence

45

What I claim as my invention, and desire to secure by Letters Patent, is—

1. In an electric-light adjuster, a stationary socket, an opening in the socket, a ball in the socket, a shank on the ball to extend 50 through said opening, a central opening through said ball and shank, said opening in the ball flared out, a cap on said ball, a central opening through said cap, said opening in the cap flared out contiguous to the flared opening of the ball, a bar, across the upper part of the socket, a flange on the socket to hold said bar, a central opening through the bar, and a spiral spring connected to the bar and the cap, substantially as described and 55 set forth.

2. In an electric-light adjuster, a stationary socket, a stationary bar across the upper part of the socket, a central opening through said bar, an opening through the lower part 60 of the socket, a ball, a shank on the ball extending through said opening, a central opening through said ball and shank, a tube secured on the shank, a reducing-collar on the end of the tube, a slideable tube in the stationary tube and extending beyond, spring-arms extending from the inner end of the slideable tube to press against the inner part of the stationary tube, an electric light connected to the extended end of the slideable tube, 65 a cap on the ball, a central opening through the cap, and a spiral spring connecting said upper bar and cap, substantially as described 70 and set forth.

In testimony whereof I affix my signature 80 in presence of two witnesses.

JOHN ALEXANDER LEGGATT.
